F. Stith

United States Patent Office.

F. STITH, OF MEMPHIS, TENNESSEE.

Letters Patent No. 88,820, dated April 13, 1869.

FIRE-TONGS.

The Schedule referred to in these Letters Patent and making part of the same.

To all whom it may concern:

Be it known that I, F. STITH, of Memphis, in the county of Shelby, and State of Tennessee, have invented a new and useful Improvement in Fire-Tongs, of which the following is a full, clear, and exact description, reference being had to the accompanying drawings, which make part of this specification, and in which—

Figure 1 represents a front view of my improved tongs, the dotted lines showing the legs open.

Figure 2 represents a horizontal section through the same, at the line L M of fig. 1.

Figure 3 represents a view in perspective of the same.

Figure 4 represents a vertical section through the same, at the line O P of fig. 1.

Figure 5 represents an edge view of the same.

In the three drawings—

A represents an elongation of the handle B, through the cross-piece F F, terminating in the two arms C C and C C', slotted, as E and E, to receive the legs D D' and D D', and to permit their radial play, as indicated by the dotted lines, and the letters D' and D', while the sides e and e', of the appliance a e c', prevent the lateral play and consequent cross-lapping incident to fire-tongs, as now or usually made.

What I claim as my invention, and desire to secure by Letters Patent, is—

The combination of the handle B, the prolongation A, and its slotted arms C C', with the legs pivoted in the cross-arms F, when all these parts are constructed and arranged as described for joint operation.

F. STITH.
